TYPEWRITING MACHINE

Filed July 29, 1924

Fig. 1.

UNITED STATES PATENT OFFICE.

FRANK C. URSBRUCK, OF NEW YORK, N. Y., ASSIGNOR TO UNDERWOOD TYPEWRITER COMPANY, OF NEW YORK, N. Y., A CORPORATION OF DELAWARE.

TYPEWRITING MACHINE.

Application filed July 29, 1924. Serial No. 728,826.

This invention relates to typewriting machines, and particularly to a device attachable to a machine equipped with decimal tabulator mechanism, the purpose of the device being to register the amount of typing performed by an operator.

A feature of the present invention is the provision of simple means for utilizing the escapement wheel shaft to drive a revolution counter.

Another feature of the invention is the provision of means for mounting the device upon a machine of the usual standard construction, requiring no special structural features or alterations to be made to the machine in applying the device thereto, the device, when mounted, being easily adjustable for properly aligning the same with its driving means.

Another feature of the invention covers means associated with the register or counter whereby the same may be readily attached or detached from the machine.

A further feature embodies an arrangement, such that when the device is attached to the machine, the parts comprising the counter and its mounting means, will be securely interlocked and held against movement by means of a single screw and nut.

The invention further provides a form of construction which is extremely simple, and due to this fact, and the few parts used, the device is inexpensive to manufacture.

Other features and advantages will hereinafter appear.

In the accompanying drawings,

Figure 1 is a section through a portion of a typewriting machine, showing my improved registering device applied thereto.

Figure 2 is a plan view, partially in section, showing the registering device attached to its supporting frame.

Figure 3 is a rear view of the registering device and its supporting frame.

Figure 4 is a perspective view, showing the several parts comprising the registering device disposed one above the other in their order of assembly.

Upon depression of type-bars, not shown, a link 10 operates to raise type-bars 11 to drive type 12 against the platen 13. A universal bar 14 is actuated by heels 15 on the type-bars 11 whenever a key is struck, and an escapement frame 16 pivoted at 17 operates dog-rockers 18 which co-operate with

an escapement-wheel 19 having a pinion 20 which runs in mesh with a carriage rack 21 connected through pivoted arms 22 to the carriage 23 to control the letter-feeding movement of the carriage. Usually a governor or braking device 24 is employed to limit the speed of the carriage when released from the letter-space escapement mechanism through the operation of a tabulator-key, and may comprise a casing 24' pivoted by means of a suitable shaft 25 in bearing supports 26 carried by a frame 27. Casing 24' contains the braking mechanism referred to, and carries a pinion 28 disposed adjacent the end of an extension 29 of the casing 24', the pinion being fixed to the end of a shaft disposed within the casing, and in connection with the braking mechanism forming a portion of the governor.

Decimal tabulator keys, not shown, cause upward movement to be imparted to a series of vertically disposed stop-bars 30 which are characterized by cut-out portions 31 forming shoulders 32 which act against a plate 33 fastened to a rock-shaft 34 journaled in extensions 27' of the frame 27 to impart motion to a rocker arm 35 secured upon the opposite side of the rock-shaft 34. The upper ends of the stop-bars 30 are arranged to be selectively projected by means of the tabulator-keys, not shown, into the path of decimal tabulator stops 38 to effect tabulating movements of the carriage when released to jump. The governor carries a rocker arm 36 similar to the arm 35, and these two arms are operatively joined by a connection 37 pivotally attached to the free ends of the arms. When any of the tabulator keys are depressed the corresponding stop-bar is raised, thus rocking the governor about its pivot through the medium of the connection 37, this action causing the pinion fixed to the end of the governor shaft to engage the carriage-rack 21 and raise said rack 21 out of mesh with the escapement pinion 20. The movement of the carriage from this point is then under the control of the governor which functions to bring the carriage to rest at the end of its run, without vibration or shock to the machine. Thus far, the mechanism described is that which has heretofore been used in the Underwood standard machines when equipped with the decimal tabulator, and its description here is given simply for a clear

100 description here is given simply for a clear 105 110

understanding of the manner in which the present invention, now to be described, is associated for the purpose of keeping track of the amount of work performed on the machine.

A bracket 39, which may comprise a sheet-metal stamping cut and bent to form, provides a base or support upon which the various parts of the registering mechanism are mounted and secured. A pair of laterally-extending ears 40 of the bracket 39 have perforations 41 therein and suitable straps 42 pass through the perforations 41 and are hooked at 43 to engage around the web portion 26' of the frame 27. Clamping nuts 42' are received in threaded relation on the outer ends of the straps 42 and draw the bracket 39 tightly against the frame 27. A platform 44, which is preferably formed in one piece with the bracket 39, has an elongated rectangular perforation 45. The platform 44 is disposed at right angles to the clamping portion or ears 40 of the bracket, and mechanism including an ordinary counter 44' is supported upon and secured to the platform. In order to adjustably mount the register or counter upon the platform 44 a seat 45' is provided and may comprise a piece of sheet-metal cut and bent over to form a dovetail slot 46 having parallel inner sides 47 which receive the correspondingly shaped dovetail base 48 of the counter 44'. The seat 45' is cut out or notched on both sides at 49 to accommodate the dovetail jaws 50 of a clamp 51 which engages the base 48 of the counter and extends partially into the perforation 45, the under portions of the jaws overlying and being slightly spaced from beveled edges 51' forming the two short sides of the rectangular perforation 45, as clearly shown in Figure 4. A threaded stud 52 suitably secured to the lower portion of the clamp 51 receives a nut 53 on the under side of the platform 44, and serves, when drawn up, to securely interlock and fasten all of the parts together, and the counter 44' upon the platform 44. It will be readily understood that the counter may be quickly and easily adjusted in the seat 45' by simply loosening the nut 53 and sliding the counter bodily within the dovetail slot 46, and that the device may be adjusted up and down by loosening the nuts 42' and moving the position of the bracket 39 and straps 42 with respect to the frame 27. The counter 44' is arranged to be indexed by means of the rotary motion imparted thereto by the escapement wheel 19, and for this purpose the shaft of the counter has a collar 54 which receives a shaft or wire 55 of relatively small diameter so as to pass without interference between the closely banked complement of stop bars 30. Set screws 56 threaded into the collar 54 securely join the shaft

or wire 55 to the registering mechanism of the counter. It will be noted that the shaft 25 is reduced at 25' so as to provide clearance for variations in assembling and adjusting the register to proper position. 70

A U-shaped piece 57 is attached to the outer end of the shaft or wire 55 and straddles a flat-sided lock-nut 58 carried by the escapement-wheel 19 to provide a driving connection for the counter.

It will be readily seen from the foregoing description of the registering device, considered in connection with the governor control and decimal tabulator mechanism, that upon operation of any one of the tabulator keys, the stop-bars 30 will act through the medium of the governor 24 to throw the carriage-rack 21 out of mesh with the escapement-pinion 20, the stop-bars co-operating with the stop 38 in determining the jump of the carriage, and that during this movement the counter will not operate. Upon operation of the typing keys the escapement-wheel or its shaft drives the counter which is provided with usual interior revolution-counting devices, and hence indexes at regular intervals upon the completion of a predetermined plurality of letter-space operations of the printing keys, and from this the actual work done by an operator of the machine may be readily computed.

Variations may be resorted to within the scope of the invention, and portions of the improvements may be used without others. 100

Having thus described my invention, I claim:

1. The combination with the carriage-escapement mechanism of a typewriting machine having an escapement shaft, of a register including a driving shaft aligning with the escapement shaft, and means carried by said driving shaft for coupling the same to said escapement shaft to transmit motion from the latter to the register. 105

2. The combination with the carriage escapement mechanism of a typewriting machine having an escapement shaft and means for locking the shaft to said mechanism, of a register including a driving shaft aligning with the escapement shaft, and means carried by said driving shaft for coupling the same to said locking means to transmit motion from the escapement shaft to the register. 110

3. The combination with the carriage escapement mechanism of a typewriting machine having an escapement shaft and a lock-nut therefor, of a register including a driving shaft aligning with the escapement shaft, and means carried by said driving shaft for coupling the same to said lock-nut to transmit motion from the escapement shaft to the register. 125

4. The combination with the carriage es-

5 capement mechanism of a typewriting machine having an escapement shaft and a lock-nut therefor, of a register including a driving shaft aligning with the escapement shaft, and means carried by said driving shaft engaging around said lock-nut to couple the driving shaft to the escapement shaft.

10 5. The combination with the carriage escapement mechanism of a typewriting machine having an escapement shaft and a lock-nut therefor, of a register including a driving shaft aligning with the escapement shaft, and a yoke member fixed to the driving shaft and engaging around said lock-nut to transmit the rotary motion of the escapement shaft to the register.

20 6. The combination with the carriage escapement mechanism of a typewriting machine having an escapement shaft and a lock-nut therefor, of a register including a driving shaft aligning with the escapement shaft, and a U-shaped member fixed to the driving shaft and engaging the lock-nut 25 upon the opposite sides thereof to couple the driving shaft to the escapement shaft.

30 7. The combination with the carriage-escapement-wheel of a typewriting machine, of a register having a driving shaft, a support for said register including a platform upon which the base of the register rests, a releasable clamping device mounted on the platform and engaging around the base of the register, whereby to secure the register to the platform, said platform including guiding means co-operating with the clamp for automatically aligning the register-shaft with the shaft of the escapement-wheel when the register is clamped, and means for coupling said aligned shafts.

40 8. The combination with the carriage-escapement-wheel of a typewriting machine, of a register having a driving shaft, a support for the register including a platform having a rectangular opening therein, a clamp mounted in and guided by said opening for engaging around the base of the register, means for securing said clamp within the opening, whereby to clamp the register to the platform and align the register-shaft with the shaft of the escapement-wheel, and means for coupling said aligned shafts.

50 9. The combination with the carriage-escapement-wheel of a typewriting machine, of a register including a driving shaft, means for coupling said driving shaft to the shaft of the escapement-wheel, a vertically-adjustable platform at the rear of the escapement-wheel, a seating device for the base of the register, and a clamp associated with said platform and seating device, whereby to hold the base secured to the platform and to guide said seating device to align the register-shaft with the escapement-wheel-shaft.

60 10. The combination with the frame and

escapement mechanism of a typewriting machine, of a register driven by said mechanism, a support for the register, said support including a platform and ears, means co-operating with said ears and frame to adjustably secure the support to the frame, a seating device for adjustably mounting the register on the platform, and means interlocking said seating device with the platform and clamping the register in position thereon.

70 11. The combination with the carriage-escapement-wheel of a typewriting machine, of a register having its driving shaft coupled to the shaft of the escapement-wheel, a support for the register, and clamping means for attaching the register to the support, said clamping means automatically aligning the register-shaft with the escapement-wheel-shaft when the register is in clamped 80 position.

85 12. The combination with the frame and escapement mechanism of a typewriting machine, of a register driven by said mechanism, a support for the register comprising a bracket including a portion arranged to be fastened to the frame of the machine and a platform having a rectangular perforation therein, a seating device for receiving the register, said seating device having a pair of oppositely disposed notches in the sides thereof arranged to overlie a portion of said perforation, a clamping member including a yoke portion disposed within the perforation and a pair of clamping fingers extending from said yoke portion, said fingers projecting through the notches and engaging the register, and means associated with said clamping member for drawing the fingers against said register to secure the same upon the platform.

90 13. The combination with the escapement mechanism of a typewriting machine having an escapement shaft and means for locking the shaft to said mechanism, of a register including a driving shaft, means carried by said driving shaft for engaging said locking means to transmit motion from said escapement mechanism to the register, a support for the register and a pair of 110 straps carried by the support, said straps including hooked portions arranged to engage around the frame to adjustably hold the register in position thereupon, the shanks of the straps being disposed closely 120 adjacent the sides of the frame whereby to guide the support when moving the same to adjusted position on the frame.

125 14. The combination with the frame and carriage escapement mechanism of a typewriting machine, of a register driven by said mechanism, a support for the register, means carried by said support and movable with respect to the frame for adjustably securing the support to the frame, and re-

leasable means engaging the base of said register and interlocking with the support to secure said register against movement thereupon.

- 5 15. The combination with the frame and carriage-escapement-mechanism of a typewriting machine, of a register driven by said mechanism, a support for the register, means for adjustably securing the support
10 upon the frame of the machine, and means

adjustably clamping said register to the support and interlocking therewith to maintain the register in proper position to be driven by the escapement-mechanism, said clamping means including a single screw-threaded ¹⁵ stud and nut for holding said register clamped and said clamping means interlocked with the support.

FRANK C. URSBRUCK.
